UNITED STATES PATENT OFFICE

2,523,009

POWER TAKE-OFF FOR COMBUSTION GASES

Robert H. Goddard, deceased, late of Annapolis, Md., by Esther C. Goddard, executrix, Worcester, Mass., assignor of one-half to The Daniel and Florence Guggenheim Foundation, New York, N. Y., a corporation of New York

Application March 11, 1947, Serial No. 733,823

1 Claim. (Cl. 60—35.6)

1

This invention relates to combustion chambers from which gases are discharged at high speed and at high temperature through a rearwardly directed nozzle. It is frequently desirable to take off power from such combustion apparatus to drive fuel feed pumps or for other useful purposes.

It is the general object of this invention to provide improved means for taking off power without interference with the flow of gases in the nozzle and with convenient adjustment as to the amount of power to be delivered.

To the attainment of these objects, a take-off tube is provided at the rear of the discharge nozzle, together with means for moving the tube toward or away from the nozzle axis. A further object of the invention is to provide improved means for cooling the take-off tube or the gases delivered therethrough.

The invention further relates to arrangements and combinations of parts which will be hereinafter described and more particularly pointed out in the appended claim.

Reference is to be had to the accompanying drawing, in which:

Fig. 1 is a plan view, partly in section, showing a combustion chamber with this invention applied thereto;

Fig. 2 is an enlarged perspective view of the intake end of the take-off tube;

Fig. 3 is a detail sectional view, taken along the line 3—3 in Fig. 2; and

Fig. 4 is a fragmentary transverse sectional view, taken substantially along the line 4—4 in Fig. 3 but showing a modified construction.

Referring to the drawing, a combustion chamber C is provided with a rearwardly extending nozzle N through which combustion gases are discharged. A take-off tube T telescopes in a conduit 8 which is mounted in a support 10. The tube T may be moved longitudinally in the conduit 8 by an adjusting screw 12.

The open end of the tube T projects into the path of the combustion gases discharged through the nozzle N, and the gases thus extracted are discharged at high speed through an auxiliary nozzle 13 and may be used to rotate a turbine 14 mounted on a shaft 15. Feed pumps or any other desired apparatus may be driven from the shaft 15.

2

The amount of power taken off by the tube T may be varied by adjusting the open end of the tube radially with respect to the nozzle N.

As the combustion gases are very hot, the intake end of the tube T is provided with a casing 20 (Figs. 2 and 3) enclosing an annular jacket space 21 to which cooling water may be supplied through a pipe 24. The water in the annular space 21 cools the intake end of the tube T, and perforations 26 discharge sprays of water which cool the stream of hot gases as the gases enter the tube T.

In the construction shown in Fig. 4, the perforations 30 in the intake portion of the tube T' are placed tangentially so that the sprays of water from the jacket space 21a within the casing 20a will form a film to protect the inner surface of the tube T', rather than being directed toward the axis for primarily cooling the gas stream.

With either construction, a desired amount of power may be conveniently taken off from the combustion gases discharged through the nozzle N, and the take-off tube is efficiently cooled and protected from high gas temperatures. Furthermore, the amount of power taken off may be conveniently regulated.

Having thus described the invention and the advantages thereof, it will be understood that the invention is not to be limited to the details herein disclosed, otherwise than as set forth in the claim, but what is claimed is:

A power take-off for gases discharged from a combustion chamber nozzle comprising a take-off pipe having a telescoping portion which projects substantially radially into the path of said gases and having an intake portion which extends a substantial distance axially toward said nozzle and approximately in alignment with the path of travel of the adjacent peripheral portion of the gas stream, means to longitudinally adjust the parts of said telescoping portion to move the intake portion of said take-off pipe toward and away from the axis of said combustion chamber nozzle to vary the power take-off, a casing which surrounds the intake end of said take-off pipe and provides an annular passage, a feed pipe which supplies a cooling liquid to said annular passage, said intake end of said take-off pipe having a plurality of cooling spray openings 50 which connect said annular passage to the in-

terior of said take-off pipe, and means to utilize the gases delivered by said take-off pipe.

ESTHER C. GODDARD,
Executrix of the Last Will and Testament of 5
Robert H. Goddard, Deceased.
